CLAIM

An ornamental design for a bracket lamp as shown and described.

DESCRIPTION

FIG. 1 is a front, right and top side perspective view of a bracket lamp showing our new design;

FIG. 2 is a rear, left and bottom side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof.

FIG. 9 is an enlarged detail view of the encircled portion of FIG. 1; and,

FIG. 10 is an enlarged detail view of the encircled portion of FIG. 2.

The broken lines shown in the drawings represent portions of the bracket lamp that form no part of the claimed design. In FIGS. 1, 2, 9 and 10, the dash-dot-dash broken lines represent sectional designations that form no part thereof.

1 Claim, 10 Drawing Sheets
